UNITED STATES PATENT OFFICE.

FRANK SLOUGH INGOLDSBY, OF ST. LOUIS, MISSOURI.

DESIGN FOR A MONUMENT.

SPECIFICATION forming part of Design No. 21,093, dated October 6, 1891.

Application filed July 29, 1891. Serial No. 401,109. Term of patent 14 years.

To all whom it may concern:

Be it known that I, FRANK SLOUGH INGOLDSBY, a citizen of the United States, residing at the city of St. Louis, in the State of Missouri, have invented and produced a new and original Design for a Monument Representing Freedom Raising the World; and I do declare the following to be a full, clear, and exact description of the same, reference being had to the accompanying drawing, forming a part thereof.

The entire outward appearance of the structure is that of a statue 1, resting upon a pedestal 2, having archways 3. The base 4 of the statue represents a pile of stone on an oblong slab 5. The statue itself is that of a

strong man in a bent position upon a pile of stone with a globe 6, representing our earth, between his shoulders, which he is raising. Chains 7, with broken shackles 8, are attached ²⁰ to the stones on which the figure rests. The dark part of the globe represents land and the light part water.

I claim—

The design for a monument, as herein described and shown.

In testimony whereof I affix my signature in presence of two witnesses.

FRANK SLOUGH INGOLDSBY.

Witnesses:

GORDON H. NOTT,
H. MCKEE.
